UNITED STATES PATENT OFFICE.

LEO V. STOELTZLEN, OF ERIE, PENNSYLVANIA, ASSIGNOR TO GENERAL ELECTRIC COMPANY, A CORPORATION OF NEW YORK.

FUEL-PUMP.

1,108,811.

Specification of Letters Patent. Patented Aug. 25, 1914.

Application filed September 19, 1912. Serial No. 721,211.

To all whom it may concern:

Be it known that I, LEO V. STOELTZLEN, a citizen of the United States, residing at Erie, county of Erie, State of Pennsylvania, have invented certain new and useful Improvements in Fuel-Pumps, of which the following is a specification.

This invention relates to pumps for supplying liquid fuel to internal combustion engines and has especial reference to oil engines, in which the fuel is delivered to the cylinders in liquid form and is ignited by the high temperature of the charge of compressed air present in said cylinders.

15 The object of the invention is to enable a speed governor, driven by the engine, to vary the quantity of oil delivered by a pump having a fixed stroke, so that the speed of the engine may be kept approximately uniform under varying loads.

To this end the invention consists in brief of a pump having a plunger making a fixed stroke and working in a cylinder which is movable longitudinally by the speed governor. At the end of each up-stroke, the plunger leaves the working part of the cylinder, so that the oil can flow in from a surrounding reservoir and fill the cylinder for the next forcing stroke.

20 In the accompanying drawings, Figure 1 is a side elevation of the pump and its driving and governing mechanism. Fig. 2 is a longitudinal section taken on the line 2—2, Fig. 3. Fig. 3 is a cross section taken on the line 3—3, Fig. 2. Fig. 4 is a cross section taken on the line 4—4, Fig. 2. Fig. 5 is a longitudinal section of a pump cylinder and plunger, the latter being at the end of its downward stroke, and the cylinder in its 25 highest position giving the greatest amount of displacement, and Fig. 6 is a similar view showing the cylinder in its lowest position, giving the least displacement.

The engine 1 is usually of the multicylinder type and a separate fuel pump is provided for each cylinder. The pumps are preferably all driven simultaneously by an eccentric 2 on a shaft 3 geared to the shaft 4 which drives the speed governor 5. The strap of the eccentric is provided with a pitman 6 whose lower end is pivoted to the free ends of two or more rock-arms 7 hinged at 8 and each carrying two or more adjustable tappets, preferably screws 9 provided with lock nuts 10. In line with each screw

is a pump plunger 11 having a head 12 on which the screw rests.

An oil reservoir or tank 13 common to all the pumps has a lid 14 supporting helical springs 15, which encircle the plungers. A 60 tubular housing 16 surrounds each spring and moves with the plunger, being held by the spring against the head 12. The housings preferably pass through openings in the lid 14, and the lower ends of the springs 65 are preferably seated on stirrups 17 depending from said lid. The springs exert a constant lift on the plungers, being compressed at each downward stroke of the pitman and released to effect the up-strokes of the plungers when the pitman rises. 70

The cylinders 18 in which the plungers work are carried on the lower end of a rod 19 arranged to be lifted and lowered by the speed governor. The cylinders are long so 75 that they extend up through the stirrups 17 which thus serve as upper guides for said cylinders. The lower ends of the cylinders fit over delivery tubes 20 rising from the bottom of the oil tanks in line with the plungers and serving as lower guides for the cylinders. At a suitable point in each cylinder are slots 21 which are always submerged in the oil so that it can always have access to the lower working portion of the 80 cylinder. 85

The tubes 20 are preferably integral with valve casings 22 located underneath the oil tank; the tubes passing up through holes in the bottom of the tank and have nuts 23 90 screwed upon them inside said tank to insure a tight joint. In each valve casing is an outwardly-opening discharge valve 24 held to its seat by a spring 25 which is retained in place by a recessed screw-plug 26 95 in the lower end of the casing. From each casing, below its valve, a pipe 27 leads to the proper cylinder of the engine. Oil is supplied to the tank through a pipe 28, the level of the oil in said tank being maintained 100 substantially constant by a float 29 controlling the valve 30 in said pipe.

The operation is as follows: The eccentric imparts to the plungers a down stroke of constant length; the up stroke being effected 105 by the springs. The governor raises and lowers the cylinders in accordance with the load on the engine. When the load is heavy, the cylinders are lifted, as shown in Fig. 5, so that the plungers eject a large quantity 110

of oil at each down stroke. But when the load is light, the governor depresses the cylinders, as shown in Fig. 6, so that the plungers, although making the same length of stroke as before, are effective in forcing the liquid during only a small part of said stroke; the portion of the cylinder below the slots 21, in which the plunger works, being quite short. It thus appears that by causing the governor to shift the cylinders up and down and thus varying the effective length of the stroke of the plungers, the quantity of fuel fed to the engine cylinders will always correspond exactly with the work which the engine is called upon to perform.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is:—

1. The combination, of an internal combustion engine with a fuel pump comprising a ported cylinder, a stationary hollow member on which the cylinder is movable longitudinally and through which fluid is discharged; a solid plunger in the cylinder which covers and uncovers the port, means for driving the plunger, means for adjusting the cylinder longitudinally on said member, a discharge valve controlling the flow of liquid through the hollow member and means for supplying fluid to the port.

2. The combination, of an internal combustion engine with a fuel pump comprising a ported cylinder, a stationary hollow member on which the cylinder is movable longitudinally and through which fluid is discharged, a solid plunger in the cylinder which covers and uncovers the port, means for actuating the plunger, a discharge valve controlling the flow of liquid fuel through the hollow member, means for supplying fluid to the port, a speed governor driven by the engine, and a rod connecting a movable part of the governor with the cylinder for adjusting it longitudinally on said member to vary the amount of fluid discharged on each working stroke of the plunger.

3. The combination, of an internal combustion engine with a fuel pump comprising a ported cylinder, a stationary hollow member on which the cylinder is movable and through which fluid is discharged, a plunger having a closed end located in the cylinder and arranged to cover and uncover the port, an eccentric for imparting to the plunger a working stroke of constant length, a spring for moving the plunger on its suction stroke, a discharge valve through which

the fluid flows from said member, a means for supplying fluid to the port, and a speed governor driven by the engine which is connected to and moves the cylinder.

4. The combination, of an internal combustion engine with a fuel pump comprising a ported cylinder, a stationary hollow member on which the cylinder is movable and through which fluid is discharged, a plunger having a closed end located in the cylinder and arranged to cover and uncover the port, a lever for moving the plunger on its working stroke, a means for imparting a vibratory movement to the lever, a spring for moving the plunger on its suction stroke, a spring pressed discharge valve in communication with the member, a means for supplying fluid to the port, a speed governor driven by the engine, and a rod that is pivotally connected to the governor and cylinder for moving the latter longitudinally on said member.

5. The combination, of an internal combustion engine with a fuel pump comprising a tank, a combined valve casing and tubular member, the latter extending through the bottom of the tank, an outwardly opening discharge valve in the casing, a cylinder in the tank having a side port and mounted to slide on said member, a plunger mounted in the cylinder and arranged to force fluid through said member past the valve, an actuator for the plunger, a spring to move the plunger on its suction stroke, a means for maintaining a sufficient amount of fluid in the tank to cover the lowest part of the port, and a speed governor arranged to move the cylinder on the member to vary the amount of fluid displaced by the plunger.

6. The combination, of an internal combustion engine, with an oil tank having a lid, a stirrup depending from said lid, a spring supported by said stirrup, a headed plunger supported by said spring, a cylinder 110 slideable on said plunger and guided by said stirrup, a delivery pipe fitting into and guiding the lower end of said cylinder, means for supplying oil from the tank to the cylinder, and a speed governor connected to said cylinder for moving it.

7. The combination, of an internal combustion engine, with a speed governor therefor, a pitman driven by said engine, a rock arm pivoted to said pitman and to a fixed support, an adjustable tappet carried by said arm, a spring lifted pump plunger in line with and moved by said tappet, a slideable cylinder for the plunger connected to said speed governor and means for supplying liquid fuel to the cylinder.

8. The combination, of an internal combustion engine, with a fuel pump comprising a plurality of independent cylinders, each cylinder having a fuel admitting port

in its side, means for supplying fuel thereto, a plunger for each cylinder which covers and uncovers the port, a tubular member on which each cylinder is movable longitudinally, a discharge valve for each cylinder through which the fuel therefrom passes, means for connecting the cylinders so that they may be moved simultaneously, and a speed governor driven by the engine which

is connected to and moves all of the cylinders.

In witness whereof, I have hereunto set my hand this tenth day of September, 1912.

LEO V. STOELTZLEN.
